APPARATUS FOR TREATING METAL ARTICLES

David C. Turnbull, Mishawaka, Ind., assignor to
American Foundry Equipment Company, Mishawaka, Ind., a corporation of Delaware

Application August 21, 1936, Serial No. 97,101

12 Claims. (Cl. 51—9)

This invention relates to apparatus for treating metal articles.

In cleaning, polishing, hardening or otherwise treating the surfaces of metal articles and particularly elongated articles and stock such as pipes, rods, strips, bars, angles, channels, beams and other members, by projecting against the members a stream of treating particles, it is desirable that the surfaces to be treated are completely and uniformly exposed to the treating stream. It is also desirable that the treatment be carried out rapidly, continuously and in an efficient manner. The articles or stock should be manipulated in a readily controlled manner and should be supported and handled in such manner that there is no detrimental bending, twisting or scraping of the articles or stock.

According to the present invention, a fan-shaped stream of treating particles moving at high velocity and defining an impingement pattern of substantial length is developed through which the elongated stock to be treated is simultaneously advanced and rotated to uniformly treat all exterior surfaces of the stock. The work piece or material is suitably supported so as to prevent bending due to its own weight or the force of the treating stream and is rotated about its axis positively and in such a manner as to prevent injurious torsional stresses from being induced therein.

The invention provides suitable apparatus for carrying out the process, comprising an abrasive-throwing wheel operative to throw a controlled stream of abrasive against the elongated stock, the wheel operating in conjunction and cooperation with conveyor mechanism which simultaneously advances and rotates the stock lengthwise through and in substantial parallelism with the elongated impingement pattern developed by the abrasive-throwing wheel. The conveying apparatus manipulates the stock so as to subject all exterior portions and areas thereof to the abrasive treating and cleaning action of the fan-shaped stream. The conveying mechanism includes one or more driving mechanisms, each including a plurality of spaced and rotatable members adapted to engage the work piece under a controlled or resilient force and suitably driven so as to advance the work piece through the treating stream. The driving members are carried on a suitable frame which is mounted for rotation about the axis of movement of the work piece and is suitably driven to rotate the work piece simultaneously with its forward movement. The driving mechanism may be sufficiently close-

ly spaced on suitable supporting means, such as rolls, guides, or the like, to support the weight of the work piece and resist the force of the treating stream. An enclosing chamber or cabinet may be provided for enclosing the stream of treating material and preventing loss of treating material or injury to workmen.

The invention provides relatively simple and rugged apparatus for effecting a combined forward and rotational movement of the work piece, which can be closely and positively controlled in close cooperation with the abrasive-throwing wheel. The work piece is carried through a relatively elongated fan-shaped stream of treating material and can be advanced at a relatively rapid rate, thus effecting substantial economy in operation over cleaning methods and apparatus heretofore employed. The work piece is advanced without being subjected to any substantial bending, twisting, rubbing, scraping, biting, or other injurious stresses or actions. The apparatus is adapted for handling various shapes and sizes of work pieces without necessitating any changes or modifications.

An object of the present invention is the provision of an improved apparatus for cleaning, polishing, hardening, or otherwise treating elongated metal articles and stock, in a rapid and efficient manner without injury thereto.

Another object of the invention is the provision of apparatus for carrying out the herein described operations which is rugged, efficient and economical to build and operate, and which can be operated with a minimum of attention.

Another object of the invention is the provision of apparatus suitable for treating articles and stock of various cross-sectional shapes and sizes without requiring any changes or adjustments in the mechanism.

Various other features, objects and advantages of the invention will be apparent from the following particular description and from an inspection of the accompanying drawings.

Although the novel features which are believed to be characteristic of this invention will be particularly pointed out in the claims appended hereto, the invention itself, as to its objects and advantages, and the manner in which it may be carried out, may be better understood by referring to the following description taken in connection with the accompanying drawings forming a part thereof, in which:

Fig. 1 is a side elevational view of one form of apparatus constructed in accordance with the in-

vention, portions of the structure being broken away to show the interior;

Fig. 2 is an end elevational view of the apparatus shown in Fig. 1;

5 Fig. 3 is an enlarged fragmentary cross-sectional view of the apparatus taken along line 3-3 of Fig. 1;

Fig. 4 is a somewhat diagrammatic longitudinal cross-section of the abrasive-throwing wheel;

10 Fig. 5 is an enlarged fragmentary cross-sectional view of the article-advancing mechanism, this view being taken along line 5-5 of Fig. 2;

Fig. 6 is a transverse cross-sectional view of the article-advancing mechanism, this view being taken along line 6-6 of Fig. 5;

Fig. 7 is a transverse cross-sectional view of the article-advancing mechanism, this view being taken along line 7-7 of Fig. 5;

20 Fig. 8 is a longitudinal cross-sectional view of the article-advancing mechanism, this view being taken along line 8-8 of Fig. 7;

Fig. 9 is a somewhat diagrammatic reduced cross-sectional view generally similar to Fig. 6 and illustrating the operation of the apparatus 25 in handling an article or length of stock of angular cross-section; and

Fig. 10 is a view similar to Fig. 9, illustrating, however, the operation of the apparatus in handling an article or length of stock having a generally rectangular cross-section.

In the following description and in the claims, various details will be identified by specific names for convenience, but they are intended to be as generic in their application as the art will permit.

35 Like reference characters denote like parts in the several figures of the drawings.

In the drawings accompanying and forming part of this specification, certain specific disclosure of the invention is made for purposes of explanation, but it will be understood that the details may be modified in various respects without departure from the broad aspect of the invention.

Referring now to Figs. 1, 2, 3 and 5 of the drawings, there is shown a housing 1 defining a treating chamber 2 and having an entrance opening 3 and an exit opening 4. Disposed in alignment with the opening 3 is a driving mechanism 5 and disposed in alignment with the exit 4 is a second driving mechanism 6 which may be similar to the driving mechanism 5. A throwing wheel 10 may be suitably mounted to project a stream *a* of treating material in the chamber 2 and against a work piece *p* extending through the housing 1 and supported by the driving mechanisms 5 and 6.

55 The wheel 10 preferably includes a plurality of spaced throwing blades 11 disposed in a generally radial arrangement and extending from adjacent the periphery of the wheel to inwardly short of the center to define a generally central space 12. Disposed in the central space 12 is an impeller 13 having a plurality of vanes 14. Surrounding the impeller 13 is a generally cylindrical control member 15 having an outlet opening 16. The control member 15 is fixed relative to the blades 11 and impeller 13, but may be adjusted angularly for the purpose of adjustably controlling the direction of flight of the treating particles, as hereinafter described.

70 The throwing blades 11 may be connected to and carried by a pair of spaced and generally parallel side plates 20 and 21. The throwing blades 11, impeller 13 and side plates 20 and 21 may be carried by a hub 17 mounted on a shaft 18 rotatable in bearings 19, whereby the impeller

13 and throwing blades 11 may be rotated as a unit. The shaft 18 may be driven by a suitable source of power, such as a motor 26, connected by a suitable drive 27 to the shaft 18.

The wheel 10 may be supplied with treating 5 material by a feed pipe 30 extending through an opening 31 in the side plate 20 and terminating adjacent the impeller 13. The treating material may be contained in a storage hopper 32 preferably disposed above the feed pipe 30 and 10 communicating therewith by a conduit 33, through which the treating material may flow by gravity to the feed pipe 30.

The treating material may include any suitable granular material, such as, for example, 15 cracked steel grits, smooth steel shot, quartz sand or other material suitable for cleaning, polishing, hardening or otherwise modifying the surface characteristics of the work piece. It will be understood that the term "abrasive" as herein used 20 includes not only materials which are inherently abrasive but also those which exert a smoothing and polishing action, and any other suitable materials.

The wheel 10 is operated by energizing the motor 26 which effects rotation of the wheel and abrasive is supplied to the wheel as above described. The abrasive is fed into the path of the impeller vanes 14 and is hurled thereby through the outlet opening 16 and into the path of the 30 throwing blades 11. The abrasive is urged along the leading faces of the throwing blades 11 and is projected from adjacent the periphery of the wheel by combined centrifugal and rotary force. The projected abrasive leaves the wheel in the 35 form of a fanlike stream having components extending throughout a substantial range of angularity and the stream forms an elongated and generally rectangular impingement pattern on a plane disposed below the wheel and generally 40 parallel with the axis of rotation of the wheel.

Side walls 40 and bottom walls 41 of the housing 1 may be formed to constitute a hopper adapted to collect the spent abrasive which has been projected by the wheel 10. The spent abrasive 45 may flow by gravity into the bottom portion of an elevator housing 42, and an elevator 43 may be provided for lifting the spent abrasive to the storage hopper 32. The elevator 43 may be driven by a motor 44 connected by a drive 45 50 to the elevator 43. Upon energization of the motor 44, the spent abrasive is lifted from the bottom portion of the elevator housing 42 and deposited in the storage hopper 32.

The driving mechanisms 5 and 6 may be substantially similar in construction and operation and hence only one of these mechanisms will be described in detail herein. Preferably the driving mechanisms 5 and 6 are disposed outside the housing 1 and at each end thereof, as shown in 60 Fig. 1. Each driving mechanism may be supported on a suitable frame 60 connected to the adjacent portion of the housing 1 by an angle 61.

Referring again to Fig. 5, the driving mechanism 5 includes a pair of spaced and generally 65 parallel stationary heads 62 rigidly secured to the frame 60, in oppositely facing arrangement. Rotatably mounted in the heads 63 is a drum 65 adapted to carry the mechanism for advancing the work piece *p*.

The drum 65 is supported at each end by a roller bearing 63 which includes a plurality of spaced rollers 66 positioned between roller rings 67, which rings carry pins 68 upon which the rollers 66 are rotatably mounted. The rollers 75

66 travel in a raceway 69 in each head 62 and a shoulder 70 on each drum retains the corresponding bearing 62 in the raceway.

The drum 65 is rotated by a suitable source 5 of power, such as a motor 71, connected by a suitable drive 12 to a speed reducer 13 driving a pulley 74. An endless flexible driving member, such as belt 75, may be trained around a pulley 74 and around the drum 65. Upon energization 10 of the motor 71 the pulley 74 is rotated and imparts corresponding rotation to the drum 65. Suitable take-up means 76 may be provided for adjusting the position of the motor 71, thereby to adjust the tension on the belt 12.

15 Also, suitable means (not shown) may be provided for maintaining sufficient tension on the belt 75.

The motor 71 also may be connected to the drum 65 of the other driving mechanism 6 (see 20 Fig. 1) by a suitable connection (not shown) or a second motor and drive (not shown) similar to that described in connection with the mechanism 5 may be provided. In either case, it is preferable that the drums 65 be driven in synchronism.

25 Disposed within the drum 65, and secured thereto, are partitions 80, 81 and 82. A sleeve 83 is secured to the partition 82 as by means of a flange 84 and extends through an opening 85 in the right-hand (as viewed in Fig. 5) head 62. 30 A second sleeve 86, having flanges 87 and 88 secured to partitions 80 and 81 respectively, extends through the partition 80 and through an opening 89 in the left-hand (as viewed in Fig. 5) head 62. The sleeves 83 and 86 are disposed substantially in alignment with each other and with the opening 3 in the adjacent wall of the housing 1 and serve as a guide for the elongated article or work piece *p* to be treated.

35 Rotatably mounted in the chamber bounded 40 by the partitions 81 and 82 and in position to engage the work piece is a pair of pressure rolls 90. Each roll 90 (see Fig. 6) preferably comprises a cylindrical portion 91 connected by a spider 92 to a hub 93. The hub 93 is mounted on a shaft 94 and suitably fixed thereon by a key 95. 45 A jacket 96 formed of resilient material, such as rubber or rubber fabric, may be telescoped over the cylindrical portion 91, in order to provide a resilient surface for engagement with the work piece *p*.

50 Each shaft 94 is journaled in bearings 98. The bearings 98 may be integral with a sleeve 99 mounted for limited sliding movement on a vertical shaft 100, preferably fixed in the drum 65. 55 The two sleeves 99 on each shaft may be resiliently urged toward each other by a coiled spring 101 anchored to lugs 102 connected to or integrally with the sleeves 99. Movement of each sleeve 99 on its shaft 100 may be limited by 60 spaced collars 103 fixed on the shaft 100.

65 It will be seen that the springs 101 tend to urge the cooperating rolls 90 toward one another until the sleeves 99 engage the inner collars 103. Thus, when a work piece of suitable diameter is inserted between the rolls 90, the latter will bear against the work piece with considerable pressure and pinch the work piece therebetween. The springs 101, however, permit the rolls 90 to be separated to accommodate a work piece of larger diameter.

70 One of the stationary heads (see Fig. 8), for example head 63, may be formed with an inwardly projecting angular flange 110 and an internal ring gear 111 may be secured therein. A pinion 112 may be fixedly carried on a shaft 113 jour-

naled in bearings 114 and 115 secured to the partitions 80 and 81. The pinion 112 is mounted in position to mesh with the ring gear 111 during the entire rotational movement of the drum 65. Fixedly carried on the shaft 113 is a worm 120 meshing with a pair of worm wheels 122 each of which is carried on a shaft 123, journaled in a bearing 124, suitably supported on the partition 80. A sprocket 125 is fixed on the shaft 123 and a chain 126 is trained over the sprocket 125 and 10 also over a sprocket 127 fixed on the shaft 94.

15 It will be seen that each roller 90 thus is connected through a positive drive to the single worm 120. Upon rotation of the drum 65, the pinion 112 is carried around the internal ring gear 111 with a planetary movement and the shaft 113 is rotated. The rotation of the shaft 113 is transmitted to and effects rotation of the pressure rolls 90.

20 The operation of the apparatus is as follows: 20 The wheel 10 is operated, as above described, to project a stream of treating material *a* in the housing 1. The motor 70 is energized to rotate the drum 65 of the driving mechanism 5 which carries the pressure rolls 90 bodily above the axis 25 of the drum 65. The rotation of the drum 65 also produces rotation of the pressure rolls 90 about their own axes by the rotation of the drum 65. The driving mechanism 6 is similarly operated.

25 A work piece *p*, such as, for example, a pipe or tube, is inserted in the sleeve 83 and forced between the pressure rolls 90, the springs 101 expanding sufficiently to permit the rolls 90 to separate and admit the work piece *p*. As soon as the 30 work piece *p* is gripped by the pressure rolls 90, the latter roll relatively thereto and advance the work piece into the chamber 2 (to the left as viewed in Figs. 1 and 5). The work piece is also rotated about its axis, owing to the rotation of the pressure rolls 90 about the axis of the drum 65. The work piece *p*, therefore, is given a screw-like movement which advances it into the chamber 2 and rotates it about its own axis.

35 As the work piece *p* passes into and through the 40 stream of abrasive *a*, it is struck by the rapidly moving particles of treating material and cleaned, polished, hardened or otherwise treated, according to the nature of the treating material. The driving mechanisms 5, 6 may be located sufficiently close to one another to support the weight of the work piece, or the portion of the material extending between the driving mechanisms, and also resists the thrust of the stream 45 on the work piece so that there is no detrimental bending of the work piece.

50 The stream *a* extends over a substantial length and strikes the work piece *p* at varying angles, thereby entering any cavities or depressions in the work piece, and effectively loosening and removing all foreign matter which may adhere to the work piece or otherwise producing the desired effect. Since the work piece is rotated, all portions of the circumference are successively turned up into position to be struck by the treating particles.

55 The work piece passes through the chamber 2 and into the second driving mechanism 6, which cooperates with the work piece in a manner similar to the driving mechanism 5. The work piece 60 is advanced out of the second driving mechanism 6 and is then ready for use or further treatment.

65 Since the rolls 90 are urged together by and are restrained against separation by the springs 101, the rolls will accommodate work pieces of varying 70

diameters, hence the second work piece of either smaller or larger diameter than the first work piece can be inserted immediately after the first work piece passes through the pressure rolls. If 5 the new work piece is smaller, the springs 101 will urge the pressure rolls 90 closer together and into engagement with the work piece. If the second work piece is larger, the springs 101 will expand and permit the rolls 90 to accommodate themselves to this larger work piece. The apparatus 10 also will accommodate work pieces which vary in diameter or cross-section through their length, the rolls 90 moving farther apart or closer together according to the cross-sectional dimension 15 of the work piece to be accommodated.

The present apparatus also is suitable for handling members of lengths of stock having cross-sections other than round. It is not necessary to change the apparatus in any way to accommodate 20 the various types of work pieces. Work pieces of various cross-sectional sizes and shapes can be fed successively as part of a substantially continuous operation, without shutting down or adjusting the apparatus.

25 Referring now to Fig. 9 there is shown diagrammatically the manner in which the pressure rolls cooperate with an angle or L-beam *n*. One of the rolls bears against the edges of the webs of the angle *n* and the other roll bears against the edge 30 or apex. The rolls 90 rotate and drive the angle *n* forwardly and at the same time the rolls 90 rotate bodily about the axis of the drum 65 and thus turn the angle *n* about this axis. It will be understood that as the angle *n* is advanced through the 35 abrasive stream *a* the angle *n* is turned about so that both the inside and outside surfaces and the edges are evenly and fully treated.

Referring now to Fig. 10 there is shown diagrammatically the cooperation between the rolls 40 and a bar *r* or other member having a generally rectangular cross-section area. It will be seen that the rolls 90 bear against the opposite surfaces of the bar *r* and thus when the rolls are rotated the member *r* is advanced through the stream. 45 The rolls 90 also rotate about the axis of the drum 65 and turn the bar *r* about its axis thereby exposing successively the several surfaces and edges of the bar *r* to the abrasive stream.

Where the work piece has a suitable cross-sectional shape as, for example, circular, it may be 50 supported within the housing 1 by a suitable number of freely rotatable rolls (not shown), suitably journaled in the housing. A jacket (not shown) of resilient material such as rubber, rubber fabric, or the like, may be provided for each roll in order to protect the roll against the wearing action of the treating particles. The rolls (not shown) preferably are suitably spaced so that the unsupported length of the work piece is 55 insufficient to permit appreciable bending of the latter.

It should be apparent from the foregoing that the present apparatus is suitable for treating a large number of different members and lengths 60 of stock having various cross-sectional shapes and sizes. By way of example, the apparatus is suitable for treating pipes, tubes, rods, strips, bars, angles, channels, beams, various metal sections, structural elements, and various other 65 elongated members and lengths of stock. The apparatus is also suitable for operating continuously upon metal material and is especially well adapted for treating metal stock which has been rolled or drawn and before it is cut into predetermined lengths. The present apparatus is sub-

stantially automatic in operation and can be installed as an element of a continuous production line.

The present method and apparatus provide complete and uniform treatment of the work 5 piece or material. The work piece or material is advanced continuously and at a predetermined and controlled rate and hence there is no opportunity for over or under treatment. The abrasive stream may have a relatively elongated 10 impingement pattern and the work piece or material may be advanced through the stream at a relatively high rate of speed, thus operating at high efficiency and low cost. By way of example, in one installation, made in accordance with the 15 present invention, a length of pipe approximately six inches in diameter was completely and satisfactorily cleaned at a rate of approximately twelve linear feet per minute. The rate of cleaning and treating can be further increased by providing the apparatus with two or more abrasive-throwing wheels each arranged to throw a stream of abrasive against the advancing work piece. The wheels may be mounted in alignment or out of alignment or above and below and at each side 20 of the work piece, as desired.

Preferably, the work piece is advanced with such pitch, that it is rotated several times in the course of its travel through the stream. However, if desired, the pitch may be so selected that 25 each portion of the surface of the work piece passes through the stream but a single time. Generally it is preferable that the several portions of the work piece be passed through the stream a number of times. It will be noted that 30 the conveyor mechanism and the work piece-supporting apparatus is so arranged that no part of the apparatus comes into contact with the stream of thrown abrasive.

The pressure rolls which engage the work piece 40 are rotated with the work piece as a unit and hence there are no torsional stresses set up with the work piece while in the apparatus. Since the rolls 90 roll relatively to the work piece there is no substantial drag or friction tending to cause 45 any twist or bending of the work piece, nor is there any scraping or rubbing of the work piece. The work piece is suitably supported against bending due to unsupported weight or due to the thrust of the treating material and thus no deformation results from treatment in accordance 50 with the present invention.

The present apparatus is relatively simple and rugged and is very compact and may be located in mills where space is at a premium. Only a single 55 abrasive-throwing wheel is required, since the work piece is continuously rotated in the stream and all portions may be treated by a single stream, although it is understood that where high speed production is required, two or more wheels 60 can be mounted in the cabinet to satisfy production requirements. The apparatus is relatively self-contained and it is necessary only to provide suitable connections for energizing the driving 65 motors.

While certain novel features of the invention 70 have been disclosed and are pointed out in the annexed claims, it will be understood that various omissions, substitutions and changes may be made by those skilled in the art without departing from the spirit of the invention.

What is claimed is:

1. Apparatus for blast cleaning elongated metal members or stock including, means for projecting a stream of abrasive particles, gripping means 75

adapted to resiliently grip the member or stock, means for actuating said gripping means to advance the member or stock through said stream, and means for turning said gripping means bodily with the member or stock and simultaneously with its forward movement.

2. Apparatus for blast cleaning elongated metal members or stock including, means for projecting a stream of abrasive particles, a plurality of 10 pinch rolls adapted to relatively grip the member or stock, means for rotating said rolls about their axes to advance the member or stock, means mounting said pinch rolls for turning movement bodily with the member or stock, and 15 driving means for turning said rolls with the member or stock simultaneously with its forward advancing movement.

3. Apparatus for blast cleaning elongated metal members including, means for projecting a 20 stream of abrasive particles, a plurality of elements adapted to frictionally engage the members, means mounting said frictional engaging elements for rotation, means for rotating said frictional elements to advance said member, 25 means mounting said frictional elements for rotation about a common axis and means for rotating said frictional engaging elements about said common axis whereby to rotate said elongated member about said common axis simultaneously 30 during the advancing movement of said member.

4. Apparatus for blast cleaning elongated metal articles including, means for projecting a stream of abrasive particles, a plurality of members adapted to frictionally engage an article to be treated, means mounting said frictional engaging 35 members for rotation about individual axis and for relative separation, means resiliently urging said frictional members together whereby to engage said article, means for rotating said frictional members to advance said article through 40 said stream, means mounting said frictional members for rotation about a common axis, and means for rotating said frictional members about said common axis whereby to rotate said article in said stream about an axis extending in the 45 direction of forward movement.

5. Apparatus for blast cleaning elongated metal articles including, means for projecting a stream of abrasive particles, a driving member, means mounting said member for rotation about an axis extending transversely to the direction of movement of the article to be treated, means for rotating said driving member whereby to advance said article forwardly through said stream, means 50 supporting said mounting means for rotation of said driving member about an axis extending in the direction of forward movement of said article, and means for rotating said mounting means whereby to rotate said article about said second axis and in said stream.

6. Apparatus for blast cleaning metal articles including, means for projecting a stream of abrasive particles, a rotatable drum, means mounting said drum for rotation, a plurality of pinch rolls carried in said drum, means for rotating said drum to turn said pinch rolls about a common axis, and means actuated by the rotation of said drum for driving said pinch rolls to advance the article through said stream.

7. Apparatus for blast cleaning elongated metal articles including, a plurality of pinch rolls, means

for projecting a stream of abrasive particles, a rotatable frame, means mounting said pinch rolls in spaced relationship on said frame, means resiliently urging said pinch rolls together against the article to be treated, means for rotating said 5 pinch rolls to advance the article through said stream, and means for rotating said frame to rotate the article about an axis extending in the direction of its forward movement.

8. Apparatus for blast cleaning elongated metal 10 articles including, means for projecting a stream of abrasive particles, a plurality of pinch rolls, a rotatable frame, means mounting said pinch rolls in spaced relationship on said frame, means resiliently urging said pinch rolls together against 15 the article to be treated, means for rotating said frame to rotate the article about an axis extending in the direction of its forward movement, and means actuated by the rotation of said frame for rotating said pinch rolls to advance the article 20 through said stream.

9. Apparatus for blast cleaning elongated work pieces including, a treating chamber, a rotatably mounted driving member, means for urging said driving member into driving engagement with 25 said work piece, means for rotating said driving member to advance said work piece through said chamber, and means for rotating said driving member and work piece about a common axis.

10. Apparatus for blast cleaning elongated 30 metal articles including, means for projecting a stream of abrasive particles, a driving member adapted to support an article to be cleaned, means for actuating said driving member to advance the article to be cleaned through said stream, and 35 means for rotating said driving member about an axis extending in the direction of forward movement of said article whereby to turn said article about said axis simultaneously with its forward movement through said stream. 40

11. Apparatus for blast cleaning elongated metal articles including, means for projecting a stream of abrasive particles, a plurality of spaced driving rolls adapted to support an article to be cleaned, means adjustably mounting said rolls to 45 widen or narrow the space therebetween, means resiliently urging said rolls toward one another to grip the article therebetween, means for rotating said driving rolls for advancing the article gripped therebetween through said stream, frame means 50 mounting said driving rolls for rotation about an axis extending in the direction of forward movement of said article, and means for rotating said frame to rotate said driving rolls whereby to turn said article about said axis simultaneously with 55 its forward movement.

12. Apparatus for blast cleaning elongated metal articles including, means for projecting a stream of abrasive particles, a rotatable frame, a member supported by said frame and adapted to 60 support the article to be treated, means for actuating said member to advance the article to be cleaned through said stream, means for rotating said frame about an axis extending in the direction of forward movement of said article whereby 65 to turn said article about said axis simultaneously with its forward movement, and driving means actuated by the rotation of said frame for rotating said driving member on said frame.
